UNITED STATES PATENT OFFICE.

GEORGE H. ERICH, OF MINNEAPOLIS, AND DAVID S. MILNE, OF FAIRMONT, MINNESOTA.

AIR-GAGE DEVICE.

1,273,165.

Specification of Letters Patent. Patented July 23, 1918.

Application filed September 24, 1917. Serial No. 193,004.

To all whom it may concern:

Be it known that we, GEORGE H. ERICH, a citizen of the United States, residing at Minneapolis, county of Hennepin, and State 5 of Minnesota, and DAVID S. MILNE, a citizen of the United States, residing at Fairmont, in the county of Martin and State of Minnesota, have invented a new and useful Air-Gage Device, of which the following is a 10 specification.

The present invention relates generally to air gages, and aims to provide a novel and improved device of that character for use in inflating pneumatic tires.

15 One object of the invention is the provision of an air gage device constructed and arranged to indicate either the pump or tire pressure at the will of the operator through the provision of novel means for that purpose.

Another object of the invention is the provision of novel means for applying the device to the valve stem of the tire.

It is also the object of the invention to 25 provide a gage device having the features above noted, which is simple and inexpensive in construction, as well as being practical and efficient in use.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed can be made within the scope of what is claimed, without departing from the spirit of the invention.

The invention is illustrated in the accompanying drawing, wherein—

Figure 1 is a median section of the device, portions being shown in elevation.

Figs. 2 and 3 are diametrical sections showing modified means for opening the 45 valve of the valve stem.

The body of the device comprises the nipple 1 and tubular member 2 disposed in parallel lines, and a transverse portion 3 connecting the adjacent ends of said nipple and member which are offset relatively to one another. The nipple 1 and member 2 are provided with the respective longitudinal bores or passages 4 and 5 therein, and the portion 3 has a port 6 transversely of the 50 nipple and member and establishing communication between the adjacent ends of the pas-

sages 4 and 5. The portion 3 is further provided with the beveled or conical valve seat 7 facing the passage 4, and against which a beveled or conical valve 8 is seatable from 60 within the passage 4 toward the passage 5, to provide a check valve against the flow of air from the nipple to the member 2, said nipple being designed for the attachment of a hose or other conductor leading from a 65 pump. One end of the portion 3 is provided adjacent to the nipple 1 with an opening 9 in alignment with and larger than the opening or port 6, and a plug 10 is normally threaded in the opening 9 to close the same, 70 a coiled wire expansion spring 11 being confined between the plug 10 and valve 8 to normally hold said valve seated. The valve 8 has a lug 12 entering the spring to hold the spring in place against the valve, and the 75 plug 10 has a recess 13 in which the spring is seated. The plug 10 when removed, permits the valve to be readily inserted and withdrawn.

The other end of the portion 3 is provided adjacent to the member 2 with a boss 14 having the opening 15 in alignment with the port 6, and a plunger 16 is slidably snugly in the opening 15 and is provided at its inner end with a recess 17 receiving the 80 end of the stem 18 of the valve 8 which projects through the port 6 and transversely through the passage 5. The plunger 16 has a rounded head 19 against which a hand lever 20 seats, said lever having one end 85 pivoted, as at 21, to an ear 22 integral with the member 2 and boss 14, whereby the hand which grasps the device around the nipple 1, can readily be used for swinging the lever 20 toward the nipple, to push the plunger 16, inwardly, thus unseating the valve 8.

The member 2 is provided with means for attaching it to the valve stem S of a pneumatic tire, and for this purpose, said member has a portion 23 extending at an angle therefrom and provided with a bell-shaped member 24, onto the rim of which is threaded a retaining ring 25 having at its edge an inturned annular flange 26 extending across but spaced from the edge of the member 24 to loosely surround the valve stem S. A conical ring or gasket 27 of rubber or other resilient flexible material is disposed within the mouth of the member 24, and is provided at its base with an outstanding annular flange 28 clamped against the edge of the member 24 with the apex 100 105 110

of the gasket projecting into said member, and a washer 29 is disposed between the flange 28 and flange 26 to space the base of the gasket from said flange 26, thereby permitting the gasket to flex toward and away from the member 24. The gasket 27 being of conical form, is provided with the thin annular lip 30 surrounding its aperture or opening 31, said lip projecting within the member 24. Thus, when the device is applied to the valve stem S, the flange 26 passes around the stem, and the end of the stem is received by the gasket 27, which yields, thereby permitting the device to be readily pushed onto the stem, instead of being screwed thereon. The air pressure within the member 24 will tend to force the gasket 27 outwardly, said gasket acting in the manner of a diaphragm, and the ring 29 permits the gasket to bulge outwardly. This, in addition to the flexibility of the lip 30, will cause the gasket to tightly embrace the valve stem, to prevent leakage. The bulging movement of the gasket, together with the pressure of the lip 30 against the valve stem, will provide a tight fit, and will also retain the device in place on the valve stem, although the device can be readily pushed on and pulled off the valve stem manually. This saves the labor of screwing the device onto and off of the valve stem, and also provides for an air-tight joint in addition to the quick attachment and detachment of the device.

In order to open the valve of the valve stem when the device is applied, a stud or member 32 is threaded into the portion 23 and projects within the member 24, said stud having a T-shaped or other suitable passage 33 therein providing for the flow of air between the members 2 and 24. A plunger 34 is yieldably united with the end of the stud 32 by means of a coil spring 35, the spring being connected to the stud and to the plunger and is arranged to contact with and move the pin 36 of the valve stem S, when the device is applied, to thereby open the valve of said stem for the flow of air therethrough.

The member 2 has a branch 37 to which is attached any suitable air gage 38 to indicate the air pressure.

In use, when the device is applied to the

valve stem S, and the lever 20 moved to open the valve 8, air can flow from the pump into the tire, and the gage 38 will indicate the pump pressure. By releasing the lever, the valve 8 will be seated, thereby shutting off the pump pressure from the gage and tire, and the gage 38 will now indicate the tire pressure. This enables the operator to inflate the tire to the desired pressure, and tests can be made from time to time, by releasing the lever 20 momentarily, so that the right pressure in the tire can be obtained accurately.

Fig. 2 illustrates a modified means for opening the valve of the valve stem. In this case the stud or member 32^a has the passage 33 as above described, a recess 32' in its free end portion slidably receiving a plunger 34^a, and a coil spring 35^a being housed within the recess 32' and surrounding the reduced end of the plunger, whereas the spring 35 above described is exposed.

Fig. 3 illustrates the plunger 34^b integral with the end of the stud 32^b so that it does not yield as do the plungers 34 and 34^a above described.

Having thus described the invention, what is claimed is:

A device of the class described, comprising a body provided at one end with a neck merging into a bell-shaped head; a gage at said end of the body; a valve disposed between the ends of the body and under the control of an operator to regulate the passage of fluid through the body; a gasket attached to the mouth of the head and having an opening; a stud threaded for adjustment into the neck and projecting into the head, the stud having a passage establishing communication between the interior of the neck and the interior of the head; a plunger projecting into the opening in the gasket; and a compression spring interposed between the plunger and the stud.

In testimony that we claim the foregoing as our own, we have hereto affixed our signatures in the presence of two witnesses.

GEORGE H. ERICH.
DAVID S. MILNE.
